207,595

STRAINER LADLE

Francis E. Gruber, St. Paul, Minn., assignor to Northwest Plastics, Inc., St. Paul, Minn., a corporation of Minnesota

Filed Dec. 8, 1965, Ser. No. 116

Term of patent 14 years

(Cl. D44—29)

FIG. 1

FIG. 2

FIG. 3

FIGURE 1 is a top plan view of a strainer ladle showing my new design;

FIGURE 2 is a bottom plan view, and

FIGURE 3 is a side elevation view.

The essential features of my design are shown in full lines.

I claim:

The ornamental design for a strainer ladle, as shown and described.

References Cited by the Examiner

UNITED STATES PATENTS

D. 180,314 5/1957 Bair ----- D44—29

JOEL STEARMAN, Primary Examiner.